CLAIM

The ornamental design for a connector, as shown and described.

DESCRIPTION

FIG. 1 is a perspective view of a first embodiment of a connector showing my new design;

FIG. 2 is a front elevational view showing the design for the connector of FIG. 1;

FIG. 3 is a rear elevational view showing the design for the connector of FIG. 1;

FIG. 4 is a right side elevational view showing the design for the connector of FIG. 1;

FIG. 5 is a left side elevational view showing the design for the connector of FIG. 1;

FIG. 6 is a top plan view showing the design for the connector of FIG. 1; and

FIG. 7 is a bottom plan view showing the design for the connector of FIG. 1.

FIG. 8 is a perspective view of a second embodiment of a connector showing my new design;

FIG. 9 is a front elevational view showing the design for the connector of FIG. 8;

FIG. 10 is a rear elevational view showing the design for the connector of FIG. 8;

FIG. 11 is a right side elevational view showing the design for the connector of FIG. 8;

FIG. 12 is a left side elevational view showing the design for the connector of FIG. 8;

FIG. 13 is a top plan view showing the design for the connector of FIG. 8; and,

FIG. 14 is a bottom plan view showing the design for the connector of FIG. 8.

The broken line showing of the connector is included for the purpose of illustrating portions of the article and form no part of the claimed design.
